PROCESS FOR THE PREPARATION OF
FLUOROCARBONS

Robert Dudley Fowler, Baltimore, Md.; assignor
to the United States of America as represented
by the United States Atomic Energy Commis-
sion

Application February 13, 1943, Serial No. 475,852

3 Claims. (Cl. 260—648)

1

This invention relates to the preparation of fluorocarbons and more particularly to a method of preparing fluorocarbons by the reaction between hydrocarbons and metal fluorides.

One object of this invention resides in the provision of an improved process of producing fluorocarbons in a relatively simple, economical and commercially feasible manner.

A further object resides in the provision of such a method characterized by the fact that fluorination of hydrocarbon compounds will take place in the absence of a catalytic agent.

A still further object resides in the production of new and hitherto unknown fluorocarbons.

Other objects will in part be obvious and in part be pointed out hereinafter.

In general, the invention contemplates the passage of a hydrocarbon vapor over, through, or in intimate association with a metal fluoride of higher than normal fluorine constituency, as for example, cobalt trifluoride CoF_3 , silver difluoride AgF_2 , or manganese trifluoride MnF_3 .

The term hydrocarbon as used hereinafter shall be construed to include all hydrocarbons, i. e., olefinic, paraffinic, aromatic, naphthenic, etc.

Any desired hydrocarbon in vaporized form may be used, for example, heptane C_7H_{16} , hexane C_6H_{14} , cyclohexane C_6H_{12} , toluene C_7H_8 , xylene C_8H_{10} , mesitylene C_9H_{12} , octane, or any iso-octane C_8H_{18} .

Any suitable apparatus may be utilized for the carrying out of the process of this invention, a specific example of which will now be described in conjunction with the accompanying drawing wherein:

The single figure comprises a schematic flow sheet.

The specific embodiment now described contemplates the use of cobalt trifluoride, a product not at present commercially available but which may be prepared as follows:

Cobalt chloride hexahydrate $\text{CoCl}_2 \cdot 6\text{H}_2\text{O}$ is dehydrated in any suitable manner to the anhydrous form (CoCl_2) and subjected to the action of anhydrous hydrogen fluoride, HF, forming the known cobalt difluoride CoF_2 according to the reaction:

cobalt difluoride may be converted to the trifluoride by direct fluorination, at any suitable elevated temperature above approximately 150°C . according to the reaction:

2

the anhydrous CoF_3 is now placed in a suitable receptacle.

Such a receptacle may take the form of a cylinder having a series of electrical or other heating elements positioned thereabout. It has been discovered that if the temperature of such a receptacle is graduated progressively from the inlet end to the outlet through a range of approximately 150°C . to 400°C . a relatively higher yield of the desired fluorocarbon as will be discussed hereinafter, will result. It has also been found that the provision of suitable means for slowly rotating the cylinder axially will obviate channelling of the CoF_3 upon the introduction of the organic compound.

The cylinder may be partially or substantially entirely filled with CoF_3 and heated to the graduated temperatures above mentioned. A hydrocarbon, C_7H_{16} , is now passed into the chamber and reacts according to the following equation:

A small quantity of an inert sweeping gas such as nitrogen may be introduced with the hydrocarbon for the purpose of clearing the reaction chamber if desired.

Upon the completion of the reaction above mentioned C_7F_{16} and HF may be drawn from the reaction chamber together and subsequently separated in any desired manner as by fractional distillation, or condensing in a cooling chamber, following separation of the two liquid phases. Yields of fluorocarbons by the above method have exceeded seventy percent in quantity of the initial hydrocarbon input.

Having reference now to the accompanying flow sheet the process will be readily understood. The left hand vertical column indicates the ingredients, chemical and physical (i. e. agitation) embodied in the process. The center vertical column designated the reactions and the third vertical column the incidental resultants.

It should here be pointed out that the CoF_2 initially used suffers virtually no quantitative loss in the process and may be reutilized as frequently as feasible.

Additionally, if desired the fluorination of the lower metal fluoride and exposure of the higher fluoride to the hydrocarbon may be carried out in the same chamber in order to avoid shifting the fluoride, if a step by step process rather than the continuous chain process above described, is desired. In such case however, care must be taken thoroughly to cleanse the reaction vessel with an inert gas between operations.

From the above it will be apparent that virtually any desired fluorocarbon may be produced by proper solution of ingredients to give a high yield of a resultant fluorocarbon. For example, exposure of CoF_3 to an octane C_8H_{18} or dodecahydrobiphenyl $\text{C}_{12}\text{H}_{22}$, will react according to the following equations:

As previously pointed out it will be understood that the use of other higher metal fluorides and other hydrocarbons will produce other fluorocarbons as may be desired.

Now from the foregoing, it will be seen that there is herein described a simple, economical and commercially practicable method for the production of fluorocarbons.

As many embodiments may be made of this inventive concept and as modifications may be made in the embodiments herein shown and described, it is to be understood that all matter hereinbefore is to be interpreted merely as illustrative and not in a limiting sense.

I claim:

1. In the preparation of perfluororganic compounds, the step of reacting a trifluoride selected from the group consisting of manganese trifluoride and cobalt trifluoride with a hydrocarbon vapor at a temperature between 150° C. and 400° C. until all of the hydrogen of said hydrocarbon has been replaced by fluorine.

2. In the preparation of perfluoro organic compounds, the step of reacting manganese trifluoride with a hydrocarbon vapor at a temperature between 150° C. and 400° C. until all the hydrogen of said hydrocarbon has been replaced by fluorine.

3. In the preparation of perfluoro organic compounds, the step of reacting cobalt trifluoride with a hydrocarbon vapor at a temperature between 150° C. and 400° C. until all the hydrogen of said hydrocarbon has been replaced by fluorine.

ROBERT DUDLEY FOWLER.
